United States Patent Office.

LUTHER W. HARWOOD, OF TROY, NEW YORK, ASSIGNOR TO FULLER, WARREN & CO., OF SAME PLACE.

Design No. 4,947, dated May 30, 1871.

DESIGN FOR A STOVE.

The Schedule referred to in these Letters Patent and making part of the same.

To all whom it may concern:

Be it known that I, LUTHER W. HARWOOD, of the city of Troy, in the county of Rensselaer and State of New York, have invented and produced a new and original ornamental Design for Stoves, of which the following is a specification, reference being had to the accompanying photographs, in which—

Figure 1 represents a stove that embodies my said design, and

Figure 2 is a view of the top.

Figure 3, a view of the top plate of the lower section, and

Figure 4, a view of the bottom plate; all of the same stove.

Like parts are marked by the same letters in the different figures.

One new feature of my invention is the design for the movable cover A, as distinguished by the rows of ornaments b, c, and d, all shaped and arranged in combination on the cover so as to appear substantially as represented in fig. 2 of the aforesaid photographs.

Another part of my invention is the ornamental design for the top plate E, as distinguished by the rows of ornaments f and g, shaped and arranged in respect to each other so as to appear substantially as shown in fig. 2.

Another part of my invention is the design for the door-frame H, as characterized by the row of ornaments i, arranged in connection with the inclined surface j, as represented in fig. 1.

Another part of my invention is the design for the top plate K of the lower section, as marked by its swelling sides l l, and ends m m, and rounded projecting corners n n n n, with the row of border ornaments o, shaped and arranged on the plate so as to appear substantially as shown in fig. 3.

Another part of my design is the pendent ornament P Q, shaped and arranged upon and cast with a panel

of a door or plate of a stove so as to appear substantially as represented in fig. 1 of the photographs.

Another feature of my invention is the design for the grate R, as indicated by the round and quarterfoil perforations s and pointed arches t, all shaped and arranged in combination so as to appear substantially as shown in fig. 1.

Another part of my invention is the design for the damper-plate U, as characterized by the circular segment molding v, with the row of ornaments w thereon, the same being shaped and arranged as shown in fig. 4 of the photographs.

Another part of my invention is the design for the bottom plate X, as distinguished by the border molding y and row of ornaments z, shaped and arranged so as to appear as represented in fig. 4.

What I claim as my invention is—

1. The design for the cover A, as hereinbefore described.
2. The design for the top plate E, as herein set forth.
3. The design for the door-frame H, as described and shown.
4. The design for the plate K, as herein described.
5. The pendent ornament P Q, shaped and arranged upon and cast with a panel of a door or plate of a stove, substantially as shown.
6. The design for the grate R, as described and shown.
7. The design for the damper-plate U, as shown and specified.
8. The design for the bottom-plate X, as herein set forth.

LUTHER W. HARWOOD.
